UNITED STATES PATENT OFFICE.

EDMOND W. T. RICHMOND, OF ROMFORD, ENGLAND.

DESIGN FOR A GAS-STOVE.

SPECIFICATION forming part of Design No. 33,873, dated January 8, 1901.

Application filed December 11, 1900. Serial No. 39,563. Term of patent 7 years.

To all whom it may concern:

Be it known that I, EDMOND WALTER TYRRELL RICHMOND, a subject of the Queen of Great Britain, residing in Summercourt, Romford, in the county of Essex, England, have invented and produced a new and original Design for Gas-Stoves, of which the following is a specification.

The accompanying drawing shows a perspective view of a gas-stove embodying my design.

The leading features of my design consist of the rectangular frame A, supported on feet B, and the open-work top C, consisting of par-

allel bars of wavy or zigzag contour, extending from front to rear of the frame A.

Below the open-work top, in plain view, are the burners D, which are annular in form at d and have arms d' resting on brackets d'' .

I claim—

The design for a gas-stove, substantially as herein shown and described.

In testimony whereof I have hereunto subscribed my name.

EDMOND W. T. RICHMOND.
